UNITED STATES PATENT OFFICE

149,580

DESIGN FOR A SWIMMING DEVICE

Harold L. Messinger, Los Angeles, Calif.

Application March 4, 1947, Serial No. 137,311

Term of patent 14 years

(Cl. D71—1)

To all whom it may concern:

Be it known that I, Harold L. Messinger, a citizen of the United States and a resident of Los Angeles, California, have invented a new, original, and ornamental Design for a Swimming Device, of which the following is a specification, reference being had to the accompanying drawing, forming part thereof.

Referring to the drawing:

Figure 1 is a perspective view of a swimming device, showing my new design;

Figure 2 is a top plan view of the device;

Figure 3 is a side elevation thereof; and
Figure 4 is a bottom plan view of the device.

I claim:

The ornamental design for a swimming device, as shown.

HAROLD L. MESSINGER.
